CLAIM

U.S. PATENT DOCUMENTS

The ornamental design for a tail module for an unmanned underwater vehicle, as shown and described.

DESCRIPTION

1,093,868 A 4/1914 Leighty
2,992,840 A 7/1961 Reynolds et al.
3,016,249 A 1/1962 Contreras et al.
3,105,453 A 10/1963 Hayes
3,744,825 A 7/1973 Cooper et al.
3,757,721 A * 9/1973 Ohishi 114/315
D235,422 S * 6/1975 Niskin D12/308
3,987,745 A 10/1976 Chaverebire de Sal et al.
4,204,806 A 5/1980 Blanchard
4,271,552 A 6/1981 Sandler
4,553,493 A 11/1985 Sadler et al.
4,919,066 A * 4/1990 Gongwer 114/338

FIG. 1 is a perspective view of a tail module for an unmanned underwater vehicle in accordance with the present invention; FIG. 2 is a front elevation view of the apparatus of FIG. 1; FIG. 3 is a right elevation view of the apparatus of FIG. 1; FIG. 4 is a left elevation view of the apparatus of FIG. 1; FIG. 5 is a top plan view of the apparatus of FIG. 1; FIG. 6 is a bottom plan view of the apparatus of FIG. 1; and, FIG. 7 is a rear elevation view of the apparatus of FIG. 1. The broken lines shown herein are for illustrative purposes and form no part of the claimed design.
